UNITED STATES PATENT OFFICE.

LEON P. ANTHONY AND RALPH W. REYNOLDS, OF LOS ANGELES, CALIFORNIA.

MACHINE FOR DESHELLING NUTS.

Application filed June 7, 1923. Serial No. 644,031.

To all whom it may concern:

Be it known that we, LEON P. ANTHONY and RALPH W. REYNOLDS, citizens of the United States, residing at Los Angeles, in the county of Los Angeles and State of California, have invented new and useful Improvements in Machines for Deshelling Nuts, of which the following is a specification.

10 This invention relates to machines for deshelling nuts.

It is an object of the present invention to provide a means whereby English walnuts may be de-shelled in such a manner as to 15 release the kernel in substantially unmutated, unbroken condition. An object is to provide a machine including means adapted to receive a single nut and to subject the received nut to the action of means for bisecting the shell and thereafter to so act upon the bisected shell as to shatter the same in such manner as to cause the practical withdrawal of the shell halves away from each other and therefore wholly release the 25 kernel from the shell.

Another object of the invention is to provide means for gripping a whole nut and for transposing the nut to and subjecting it to the action of saw means, whereby the 30 shell is bisected between its ends. Another object is to provide means for relatively separating and at the same time shattering the shell halves in such manner as to wholly release the nut kernel. An object is to provide means for presenting an individual nut to a sawing mechanism and concurrently rotating the nut while engaged by the mechanism so that the shell will be bisected between its ends.

40 A further object is to provide a machine including means for sawing through the shell of a walnut without passing into or through the meat or kernel of the nut, and to provide means for holding and at the same time 45 rotating the nut presented to the sawing means, and to provide means for relatively shifting the nut sawing and nut holding means, and to provide means for subjecting the divided shell to a shattering action and 50 to clear the shell sections from the nut kernel.

An additional object of the invention is to provide a de-shelling machine including means for yieldingly receiving a nut and 55 whereby the nut may be bodily shifted and presented to the action of a sawing means

and then set back away from the sawing means, and in the set back position subjected to action of means for shattering the bisected shell. An object is to provide 60 means movable from the shell shattering position to an initial or zero position in readiness for the reception of or to be loaded with another nut.

Other objects and advantages will be 65 made manifest in the following specification of an embodiment of the invention illustrated in the accompanying drawings, wherein—

Figure 1 is a plan of the machine in the 70 unloaded, zero or starting position, certain of the parts being in section.

Fig. 2 is a front elevation of the machine in the starting position, with the parts as disclosed in Figure 1.

Fig. 3 is a plan of the machine with the carriage thereof in the second or nut sawing position of the parts; parts of the mechanism being in section.

Fig. 4 is a vertical, longitudinal section of 80 the machine showing the parts in nut gripping position, and indicating the starting position of the loaded parts.

Fig. 5 is a rear elevation, parts being in section.

Fig. 6 is a transverse section approximately on line 6—6 of Figure 1.

Fig. 7 is a transverse section approximately on line 7—7 of Figure 1.

Fig. 8 is an end elevation looking toward 90 the left hand end of the machine as shown in Figure 1.

Fig. 9 is a transverse section on line 9—9 of Figure 3, showing the parts in sawing position.

Fig. 10 is a plan and longitudinal section showing the nut holding means in set back position from saws, and showing the claws in gripping position.

Fig. 11 is a plan and longitudinal section 100 of the nut holding means with the claws retracted in shell shattering position.

Fig. 12 is an end elevation showing position of parts to retract or set back the nut holding means from the sawing means.

Fig. 13 is a cross section approximately on line 13—13 of Figure 10, showing the nut carrier in set-back position to clear the sawing means.

Fig. 14 is an end elevation of the parts in 110 the position assumed in the shell shattering action.

Fig. 15 is a cross section showing the mechanism set-back position of the carriage cam.

The mechanism of the present machine 5 may be considered as divisible into two principal combinations; one for receiving an individual nut which is to be de-shelled so as to accomplish the removal of the nut kernel from the nut without material laceration 10 or fracture, and the other operative to bisect the nut while it is carried by the receiving means. These organizations or mechanisms are preferably mounted upon any suitable frame, which may be called a bed 15 or table 2, and preferably mounted on this is a suitably sized motor M, having its shaft provided with a worm pinion 3 engaging a worm wheel 4, which is secured on a main shaft 5 extending longitudinally of the 20 frame and supported at a suitable height above the bed 2 as in bearings 6. Power is transmitted from the main shaft 5 by a suitable timing gear, which may include a sprocket wheel 7 and its chain 8, extending 25 transversely toward the rear of the machine and engaging a sprocket pinion 9, secured on a countershaft 10.

The bed is provided with upwardly extending, transversely disposed webs or frame 30 members 11, through which the main shaft 5 passes, and the top, inside faces of the webs are provided with guideways 12 and also with outwardly extending flanges 13, the tops of which are in a common plane, as 35 are also the guideways 12. Mounted between the webs 11 for transverse reciprocation is a carriage, which may include a longitudinal bridge 14, having upstanding end flanges 14^a with ribs 14^b slidably mounted in 40 the guideways 12.

The carriage structure is designed to be transversely reciprocated in a timed action by suitable means preferably including a carriage operating cam 15, secured on the 45 main shaft 5 and engaging a cam roller 16 mounted in a bifurcated lever arm 17, which is firmly secured on a rock-shaft 18, mounted in the webs 11 and extending through the same sufficiently to receive on its ends carriage driving arms. These arms are shown 50 as of telescopic form and include sleeve portions 20 and pin portions 20^a sliding in the sleeves and being pivotally mounted at their upper ends on fixed pivot pins 21, mounted 55 in substantial hub portions 14^c on the carriage 14. These hub portions extend outwardly from the ends of the carriage and operate in elongated apertures 11^a in the webs 11 to provide for the necessary degree 60 of movement of the carriage during and by rotation of the cam 15.

This cam is clearly shown in outline in 65 Figure 13 as a low spot 15^a which, when engaged by the cam roller 16, permits the carriage and its lever arms to be retracted to

what might be considered the zero or starting position under the action of a substantial spring 22, which may be connected to the lever arm 17 and to a fixed part as a pin 23 on the bed 2. The main or cam shaft 5 70 rotates the cam in a direction indicated by the arrow thereon in Figure 9, and this rotation causes the carriage to be shifted to its full limit of movement toward the opposite or rear side of the machine, as is indicated, when the cam roller 16 is engaging the high spot of the cam. When the carriage is thus thrown to the far position, it is sustained there by the high spot of the cam 15 for a predetermined length of time, 80 during which a nut holding means is rotated while a nut is presented to the action of a bisecting and preferably sawing means.

As soon as the sawing has been completed around the nut, which is rotated meanwhile, 85 the carriage is then permitted to return to the set-back position by a lower portion 15^b of the cam following the high portion and preceding the low spot 15^a. The carriage 90 is held in the set-back position for a predetermined length of time, during which the sections of the shell, which latter has previously been bisected preferably medially between its ends, are subjected to a separating 95 action and then to a shattering action, so that the kernel of the nut is fully freed from the sections of the shell and thus permitted to drop clear of the shell fragments.

The nut-holding, rotating and shell-shattering means. 100

The carriage 14 is provided with coaxially arranged and suitably spaced, substantially cylindrical boxes 25, which may be formed integrally with or otherwise provided at the 105 upper portions of the carriage ends, and these boxes have cylindrical bores in which are preferably arranged renewable bushings 26, which are shown as projecting forwardly and rearwardly from the respective boxes 25 and form journals for slidable plungers 27, having outwardly extending tails 27^a overhanging the top flanges 13 of the frame webs 11. The plungers 27 are designed for reciprocation without rotation in the bushings 26, and are adapted to be reciprocated by suitable means, which include means adapted to yieldingly shift the plungers inwardly toward each other. 110

Such means, as shown, includes a substantial spring 28, the ends of which are connected to bails 29 which in turn are pivotally connected at 30 to lever arms 31, of which one is disposed on each side of the boxes 25, and which have their lower ends pivoted at 32 to the carriage structure 14. The upper ends of the lever arms 31 are pivotally connected at 33 to short links 34 extending along the sides of the boxes 25 from pivot pins or screws 35 which extend out- 115 120 125 130

wardly from the sides of the respective plungers 27, as clearly shown in the sectional portion of Figure 3. The pivot pins 35 of each plunger 27 are shown as in diametrically opposite position, and the side walls of the bushing 26 are slotted at 26^a to provide for the desired degree of axial movement to the plungers 27.

Each of the plungers is provided with a coaxial anvil rod 40, projecting rearwardly from each plunger, and, in one position of the elements, being supported by fixed buttresses 41, overhanging the tails 27^a of the plungers. The forward ends of the anvil rods 40 are provided with concaved heads or anvils 42, and the anvils are normally thrust toward each other inwardly at the inner ends of the plungers 27, as by springs 43, housed within the plunger structure and bearing 20 against pins 44 or other shoulder-forming means provided by the anvil rods.

The plunger bodies 27 are provided at their inner ends with cylindrical heads 45, and these are connected to the plunger bodies 27 by any suitable means permitting rotation of the heads 45 in the bushings 26, independently of the plungers but connecting the heads to the plungers so that the heads will be reciprocated by and with the plungers. Such a means is clearly shown in Figure 4 as including inwardly flanged, segmental bands 46, the flanges of which overlap the abutting, grooved ends of the respective plungers, and their heads 45. The plunger heads 45 are shown as provided with peripheral gear-teeth 47, which are adapted to be moved into mesh with semi-circular, parallel, coaxial gears 48, which are secured on the countershaft 10 at the rear of the machine, and which is driven, as previously described, by the sprocket connection with the main shaft 5. The projecting portions of the bushings 26 are slotted at 26^a to receive the contiguous, segmental gears 48.

45 The rotating plunger heads 45 are provided with means for receiving a nut which is to be de-shelled while the carriage is in the front or starting position, Figure 1. The nut receiving means includes the yieldingly mounted anvils 42 and a suitable number of claws 50, pivotally mounted as at 51 on the respective heads 45, and being normally drawn inwardly or contracted as by means of springs 52. The claws 50 of the opposite heads have relatively offset or staggered portions so that during the operation of the machine, the teeth 50^a of the claws can come into peripheral alignment around the nut N. When the machine is in the starting position, a nut is forced in between the yielding claws and between the opposed anvils 42, these spreading outwardly to permit the arrangement of the nut longitudinally and substantially coaxial with the anvils.

As soon as the nut carriers have been thus loaded, the cam 15 forces the carriage rearwardly to a position bringing the gear teeth 47 of the plunger heads 45 into mesh with the segmental gears 48, as shown in Figure 70. 3. The timed position of the segmental gears is such that in one-half revolution thereof while engaging the plunger head gear teeth, the plunger heads will be rotated 75 a turn or more and this will cause the nut to be revolved on its own axis while presented to a bisecting means.

The nut bisecting means.

It is desirable to provide means for severing a nut shell circumferentially while being rotated by the nut carriers and to provide means so operative as to operate upon nuts of an average size, according to sorting grades, and further, to provide means operative to sever the shell without reaching or penetrating the kernel. A form of shell severing means is here shown as including a disc saw 54, which is secured on a short shaft 55, journaled in an arm 56 of an outwardly extending bracket 57, which is pivotally mounted on a supporting member which, in the present case, consists of a high-speed shaft 58, shown as arranged below the segmental gear shaft 10, and being supported 80 in bearing standards 57. This shaft 58 is shown as independent of the drive mechanism of the machine and is provided with an independent motor 60, transmitting 85 power as by a belt 61 to a pinion 62 secured on the shaft 58. The saw shaft 55 is provided on its outer end with a pulley 55^a, and this is engaged by a belt 63 extending down to and being driven by a pulley 64, secured 90 on the shaft 58. 95

Disposed in close juxtaposition to and spaced from and coaxially with the saw 54 is another and somewhat smaller saw 65, which is secured on a shaft 66, mounted in an arm 56^a of the bracket 57, and on the outer end of which shaft is secured or formed a pulley 66^a, having a driving belt 67, engaging a driving pulley 68 fixed on the shaft 58. From this it will be seen that the saws 54 and 65 rotate at a suitable rate of speed and are driven by the shaft 58 so that when the nut N is shifted so as to be rotated by the segmental gears 48, the shell will be quickly sawed through.

To provide for the automatic compensation of the saw mechanism to properly position the same upon presented nuts of different sizes, the bearing bracket 57, as stated, is yieldingly mounted, and its upper portion swings in an approximately horizontal arc, and the bracket is normally yieldingly thrust inwardly, as toward the nut to be severed, by means of a spring 70, one end of which bears on a collar 71 on an adjustable post 72, at the rear of the ma-

chine, and the upper end of the spring engages a washer 73, bearing against the rear, bifurcated end of an arm 74 of the bracket. The upper end of the screw post 72 is provided with a head 72^a, and by adjustment of the screw post, the inward movement of the bracket arm 57 is regulated. This initial regulation is made according to a grade size of nuts to be run, and to compensate for slight variation in the diameters of the nuts of the given grade, the bracket 74 is adapted to yield and spring back against the reaction of the spring 70.

Means are provided for determining the depth of penetration of the larger saw disc 54 so that it will not cut into the kernel and yet to accomplish the complete peripheral cutting of a kerf. Such means includes a gauge finger 75, secured to the bracket 57 carrying the saws, and this finger has its upper, effective end disposed close to but spaced from the saw teeth of the smaller saw 65, so that the latter can rotate freely without engaging the finger. The front, effective face of the finger 75 is shown as slightly concave to approximate the cylindrical shape of the shell of the nut.

English walnuts have a characteristic longitudinally extending shell ridge or bead around each side, and in order to provide for the proper cutting action of the saw disc 54, the gauge finger 75 must pass through the nut band or ridge and engage the peripheral face of the shell. It is for this purpose that the smaller disc saw 65 is provided and is arranged in close juxtaposition to the bisecting saw 54. In operation of the machine, while the nut is rotating, the saw 54 cuts around and through the shell and is pressed inwardly by the spring 70. This inward sawing movement brings the smaller saw disc 65 against the longitudinal band or bead of the nut and this is cut at diametrically opposite points during the rotation of the nut, until the gauge finger 73 is permitted to pass into the kerfs or notches made in the nut band by the saw 65, and then the finger 75 engages the surface of the shell and, bearing on the same, prevents further inward movement of the saw 54.

In timed sequence, the cam, in its rotation, presents the set-back face 15^b to the roller 16, and the spring 22 retracts the carriage 14 sufficiently to clear the nut from the saws. This action disengages the shell from the saws and also disengages the plunger head gear teeth from the segmental gears 48, so that the plunger heads come to rest.

Means are provided for shifting the plungers and the plunger heads with their claws toward each other so as to shift the claws in a position to enable their tips 50^a to spring into the peripheral kerf, and thus enable the shell halves to be separated from

each other by an axial movement. To accomplish this inward shifting movement of the plungers 27, their tail portions 27^a are provided with downwardly extending lugs or rollers 27^b, and these slide along contiguous guide rails 13^a provided along the flanges 13 during the rearward movement of the carriage 14. At the rear ends of the flanges 13 there are provided switches 78 in the form of flat locks which are secured on the upper ends of the vertical rock shafts 79, suitably journaled in the frame of the machine. The switches 78 have radial slots 78^a into which the plunger rollers 27^b pass from the guide rails 13^a when the carriage is shifted to the shell sawing position. The switches 78 are thrown inwardly, or toward each other, after the carriage has been set back to clear the nut from the saws, and thus force the plungers inwardly toward each other to permit the claws 50 to snap into the shell kerf. This inward action of the switches 78 is secured by rotation of their rock-shafts 79; these being provided with radially extending, slotted lever arms 80, which, in the starting position of the machine, Figures 1 and 6, extend straight outwardly from the frame walls 11 and engage respective rollers 81, provided on the rear ends of respective links 82, which are disposed in transverse position and are shown as slotted at 83 at their rear ends to receive the slotted levers 80.

Each link 82 has at its front end a pocket 83, extending from top to bottom, and also has in the side walls of the pocket a longitudinally extending slot 84, through which passes the main driving shaft 5. Disposed in each pocket of each link 82 is a cam 85, secured on the main shaft 5. These cams are designed to engage lugs or rollers 86, mounted in transverse position across their links 82, and which are secured as by means of set screws 87, Figure 6. Also secured on the shaft 5 are cams 90, and these cams are designed to engage rollers 91, provided on the contiguous faces of the links 82. While the cam 15 is supporting the carriage in the set back position (Figure 13) the cams 90 engage the rollers 91 of the transverse links 82, and shift these links forwardly, as shown in Figure 12, with the result that the switches are turned inwardly to the dotted line positions shown in Figure 10. This action of the switches shifts the plungers and the plunger heads and their fingers inwardly toward each other, and the claws drop into the saw kerf in the shell.

Continued rotation of the cam shaft 5 brings the cams 85 to the position shown in Figure 14, when these cams, by engaging the rollers 86, thrust the links 82 rearwardly, as shown in Figure 14, the result of which is to reverse the movement of the switches 78 and shift the plungers away from each

other, with the result that the shell halves are pulled apart and loosened from the kernel. The outward movement of the switches 78 is shown in dotted lines in Figure 11.

5 The switches, in their outward movement, are designed to engage lugs or rollers 27^c, provided on the lower faces of the tail portions 27 of the plungers, and shift the rollers 27^c to positions on the outside of fixed 10 rails or guides 13^b on the flanges 13 so that, in the continued rotation of the carriage cam 15, the guide rollers 27^c will be drawn from the switch ends onto the outside faces of the rails 13^b and thence run along these 15 faces to the front ends of the rails while the carriage is pulled forwardly. At the end of the forward movement of the carriage, the rollers 27^c snap around the front ends of the guides 13^b under the action of the 20 plunger contracting spring 28, thus bringing the carriage and the plungers to the zero or starting position again.

The shell shattering action.

25 During the outward movement of the switches 78, by means of the action of the cams 85, the plungers and their heads and claws, as stated, move away from each other and this movement is utilized for breaking 30 up or shattering the shell halves. When the shell grabbing means are separating, the anvil rods 40 are held against outward movement with their plungers by means of the abutments 41, with which they are coaxially 35 aligned during the shell pulling movement of the parts. These abutments, therefore, hold the anvils 42 against movement while the plungers and their heads and claws 50 pull the shell halves back against the respective anvils 42. The unyielding anvils 42 support the ends of the shell halves and the result is that the claws, moving backwardly over the anvils 42, break the same down in small pieces and thus fully release the kernel, which will discharge free from the shell 45 fragments and these will fall away when, if by chance, they are retained until the plungers are shifted again to the forward position of the carriage.

50 The switches 78 will be returned by their cams 90 to the intermediate and normal position shown in Figure 1, with their slots or mouths 78^a presented along the fixed guide rails 13, so as to again receive the plunger 55 rollers 27^b on the next rearward movement of the carriage.

Means are provided for yieldingly holding the rock-shafts 7 and 9 with their levers and switches in the normal, intermediate 60 position, and such means is shown as including a spring tongue 95, attached to each rock-shaft and engaging adjustable set screws 96, provided therefor. These springs permit the rock-shafts to be turned the 65 necessary extent in either direction and serve

to restore the shafts to the normal, idle position thereof.

Since the claws 50 swing with their plungers, it may be that the claws will stop in substantially opposite relation, and it is desirable to provide for the movement of the claws in closely to the kerf in the shell and therefore, as shown in Figure 1, the claws are of wedge-shaped form presenting acute, inner ends so that the claws will slide past 75 each other if in opposition.

In some cases, it may be desirable to shift the saws 54 and 65 relatively so that their front edges can be moved substantially 80 into a common plane. This is accomplished by providing one or the other of the shafts in an adjustable bushing, as 66^b, Figure 1. This bushing is adapted to be shifted laterally and may be secured by set screws 100, or otherwise mounted and secured. 85

The operation is as follows:

Assuming that the machine has been working and is still running, a complete series of operations or actuations with reference to one nut begins immediately after the previous nut has been de-shelled, as shown in Fig. 11. At this time the cam roller 16 is at the last end of the lower cam portion 15^b and the carriage 14 is holding the claws 50 and the shattered nut shell out of line 90 with the saws 54. At this time the slotted levers 80 are engaged by the rollers 81 and the rollers 81 are moved backwardly to turn the switches to move the rollers 27^c outwardly to pass outside of the guides 13^b. 95

Continued operation causes the roller 16 to move to the low cam spot 15^a, thereby moving the carriage 14 forwardly as shown in Figs. 6 and 7 and the claws 50 are spread apart transversely and longitudinally ready 100 to receive a new nut. The operator places the new nut in position and the roller 16 moves to the high spot on the cam 15, the carriage 14 moves backwardly and the claws 50 grip the nut as shown in Fig. 4 and continues 105 to move backwardly to bring the nut into engagement with the saws 54 and 65 as shown in Fig. 9. During this operation the guide rollers 27^c pass forwardly along the outside faces of the rails 13^b and run along these 110 faces to the front ends of the rails while the carriage is pulled forwardly. At the end of the forward movement of the carriage the rollers 27^c snap inwardly around the front ends of the rails 13^b under the action of the plunger contracting spring 28. The operator should hold the new nut in place to be 115 engaged by the claws at this time.

At this time the guide rollers 27^b pass inside of the guide rails 13^a and as the carriage 14 moves backwardly the switches 78 are turned by the rollers 81 moving forwardly so that the guide rollers 27^b pass into the radial slots 78^a.

As the nut is brought into engagement

with the saws the segmental gears 48 engage the gear teeth 47 and rotate the claws 50 to rotate the nut against the saws and cut a slot around the nut as shown in Figs. 5 3 and 9. After the slot has been cut the 10 roller 16 moves to the front end of the lower cam 15^b, thereby moving the carriage 14 backwardly slightly and moving the claws 50 into the slot in the nut as shown in Fig. 10. As the carriage moves the slotted 15 nut away from the saws the anvil rods 40 are brought into alinement with the buttresses 41, the rollers 81 move forwardly thereby turning the switches 78 and pushing 20 the guide rollers 27^b to push the claws 50 toward each other until the tips of the claws enter the slot in the nut as shown in Fig. 10. Then the rollers 81 move backwardly, thereby 25 pulling the guide rollers 27^b outwardly and pulling the severed sections of the nut shell apart and against the heads 42 and pulling the rods 40 against the buttresses 41, and continued operation of the switches 78 under the action of the rollers 81 pulls upon 30 the rims of the severed shell sections against the heads 42 and shatters the shells as shown in Fig. 11, thus ending the series of operations where it started.

Further embodiments, modifications and 35 variations may be resorted to within the principle of the invention.

What is claimed is:

1. A machine for de-shelling nuts, comprising, in combination, shell severing means, and means for gripping and presenting a nut to the severing means and for rotating the nut while presented to the severing means, said gripping means being operative to pull apart the sections of the severed shell.

2. A machine for de-shelling nuts, comprising, in combination, shell severing means, and means for gripping and presenting a nut to the severing means and for rotating the nut while presented to the severing means, said gripping means being operative to pull apart the sections of the severed shell and being adapted to shatter the severed shell sections.

3. A machine for de-shelling nuts, comprising, in combination, shell severing means, and means for gripping and presenting a nut to the severing means and for rotating the nut while presented to the severing means, the severing means including a yieldingly mounted, rotary saw.

4. A machine for de-shelling nuts, comprising, in combination, shell severing means, and means for gripping and presenting a nut to the severing means and for rotating the nut while presented to the severing means, said severing means including juxtaposed, rotary saws.

5. A machine for de-shelling nuts, comprising, in combination, shell severing

means, and means for gripping and presenting a nut to the severing means and for rotating the nut while presented to the severing means, said severing means including juxtaposed, rotary disc saws.

6. A machine for de-shelling nuts, comprising, in combination, shell severing means, means for gripping and presenting a nut to the severing means and for rotating the nut while presented to the severing means, and means for yieldingly supporting the severing means whereby the latter are adapted to shift to compensate for variation upon nuts of different size.

7. A machine for de-shelling nuts, comprising, in combination, shell severing means, means for gripping and presenting a nut to the severing means and for rotating the nut while presented to the severing means, and stop means for determining the degree of penetration of the severing means into the nut being operated upon.

8. A machine for de-shelling nuts, comprising, in combination, shell severing means, means for gripping and presenting a nut to the severing means and for rotating the nut while presented to the severing means, and stop means for determining the degree of penetration of the severing means into the nut being operated upon, the severing means being yieldingly mounted to compensate for action upon nuts of different size.

9. A machine for de-shelling nuts, comprising, in combination, shell severing means, and means for gripping and presenting a nut to the severing means and for rotating the nut while presented to the severing means, said severing means including a pair of juxtaposed disc saws, one of which is adapted to peripherally saw the shell of the presented nut and the other of which is operative to cut the longitudinally circumferential shell bead.

10. A machine for de-shelling nuts, comprising, in combination, shell severing means, and means for gripping and presenting a nut to the severing means and for rotating the nut while presented to the severing means, said severing means including a pair of juxtaposed disc saws, one of which is adapted to peripherally saw the shell of the presented nut and the other of which is operative to cut the longitudinally circumferential shell bead, and stopping means operative to engage the shell to limit the inward penetration of the sawing means.

11. A machine for de-shelling nuts, comprising, in combination, shell severing means, means for gripping and presenting a nut to the severing means and for rotating the nut while presented to the severing means, said severing means including a pair of juxtaposed disc saws, one of which is adapted to peripherally saw the shell of the

- presented nut and the other of which is operative to cut the longitudinally circumferential shell bead, and stopping means operative to engage the shell to limit the inward penetration of the sawing means, said stopping means being adapted to pass into the notches sawed into the shell bead. 5
12. A machine for de-shelling nuts, comprising, in combination, shell severing means, means for gripping and presenting a nut to the severing means and for rotating the nut while presented to the severing means, said severing means including a pair of juxtaposed disc saws, one of which is adapted to peripherally saw the shell of the presented nut and the other of which is operative to cut the longitudinally circumferential shell bead, and stopping means operative to engage the shell to limit the inward penetration of the sawing means, said stopping means being adapted to pass into the notches sawed into the shell bead, and means for yieldingly supporting the stopping means and the saws against the pressure of the presented nut. 15
13. A machine for de-shelling nuts, comprising, in combination, shell severing means, means for gripping and presenting a nut to the severing means and for rotating the nut while presented to the severing means, and means for shifting the nut receiving means to the severing means and holding the receiving means during the severing action, and then withdrawing the nut receiving means from the severing means. 30
14. A machine for de-shelling nuts, comprising, in combination, shell severing means, means for gripping and presenting a nut to the severing means and for rotating the nut while presented to the severing means, and means for shifting the nut receiving means to the severing means and holding the receiving means during the severing action, and then withdrawing the nut receiving means from the severing means, said shifting means being operative to withdraw the nut receiving means in intermittent steps. 40
15. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, said shifting means being operative to withdraw the nut receiving means in intermittent steps, and means for relatively separating the elements of the nut gripping means to pull the sections apart. 50
16. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, said shifting means being operative to withdraw the nut receiving means in intermittent steps, and means for relatively separating the elements of the nut gripping means to pull the sections apart. 60
17. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, said shifting means being operative to withdraw the nut receiving means in intermittent steps, and means for relatively separating the elements of the nut gripping means to pull the sections apart during one of the withdrawing steps and for shattering the separated shell sections. 70
18. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, and a main drive shaft for actuating the nut receiving means and the shell section separating and shattering means in timed sequence. 80
19. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, and a main drive shaft for actuating the nut receiving means and the shell section separating and shattering means in timed sequence, the severing means having an independent drive. 100
20. A machine for de-shelling nuts, comprising, in combination, shell severing means, means for gripping and presenting a nut to the severing means and for rotating the nut while presented to the severing means, means for shifting the nut receiving means to the severing means and holding the receiving means during the severing action, and then withdrawing the nut receiving means from the severing means, and a main drive shaft for actuating the nut receiving means and the shell section separating and shattering means in timed sequence, the severing means having an independent drive. 110

means, means for shifting the nut receiving means to the severing means and holding the receiving means during the severing action, and then withdrawing the nut receiving means from the severing means, and a

ing and shattering means in timed sequence, the severing means having an independent, high speed drive.

10

In testimony whereof we have signed our names to this specification.
